FIG. 5

UNITED STATES PATENT OFFICE

JULIAN L. PERKINS, OF WEST SPRINGFIELD, AND HIRAM D. CROFT, OF SPRINGFIELD, MASSACHUSETTS, ASSIGNORS TO PERKINS MACHINE AND GEAR COMPANY, OF WEST SPRINGFIELD, MASSACHUSETTS, A CORPORATION OF MASSACHUSETTS

WASHING MACHINE CARRIAGE

Application filed September 20, 1928. Serial No. 307,258.

Our invention relates to carriers or carriages adapted to rest and to be moved about on the floor, and more particularly to such carriages for and as parts of portable washing machines; and the primary object of our invention is to produce a carriage of this character which is capable of being easily and conveniently moved about on the floor, and of remaining fixed and stationary on the floor wherever placed, such carriage being comparatively simple and inexpensive in construction, capable of serving as the supporting base of a machine, such as a washing machine, and which is highly practical and efficient.

It is necessary to move a washing machine about more or less, especially if such machine be kept in some out-of-the-way place when not in use, from which it must be taken for use, to be subsequently returned thereto as is almost invariably the custom, and this calls for more strength than many women can safely put forth, hence another object of our invention is to provide the machine with a base or carriage so constructed as to eliminate all such difficulty. To this end the carriage is counterweighted, the motor preferably being utilized as the counterweight. Constructed and counterweighted as it is, the carriage and the whole machine can be moved even by a child.

A washing machine mounted on casters or wheels alone is not sufficiently stable, when the carriage of said machine is at rest and the mechanism of said machine is in action, and said carriage is liable to move and interfere with and hinder the operator.

Other objects and advantages will appear in the course of the following description. We attain the objects and secure the advantages of our invention by the means illustrated in the accompanying drawings, in which—

Figure 1 is a side elevation of a washing machine carriage which embodies a practical

form of our invention, portions of the tub and the wringer column mounted on said carriage being broken out to economize space; Fig. 2, a central, vertical section through the foot of said carriage, taken on lines 2—2, 50 looking in the direction of the associated arrow, in Fig. 1; Fig. 3, a bottom plan of said carriage; Fig. 4, a side elevation of a modified form of carriage, and, Fig. 5, a bottom plan of the same. 55

Similar reference characters designate similar parts throughout the several views.

Our invention resides in a carriage comprising a body mounted on revoluble and non-rotary members, the latter in any case 60 comprising one or more anti-slide elements or members, whereby said carriage is rendered capable of being held stationary on the floor, or of being raised to take the anti-slide member or members off of the floor, 65 moved on the revoluble member or members to the desired place, and let down again with said anti-slide member or members back on said floor.

In the example illustrated in Figs. 1 and 70 3, the body of the carriage consists of a transmission case 1 provided at the forward end underneath with a socket member 3, and at the rear end above and below with two pairs of lugs 4 and 4', respectively, to which lugs 75 an electric motor 5 is fastened by bolts 6. Extending obliquely from opposite sides of the body or case 1, adjacent to the rear end thereof, are two arms 7. The arms 7 are on opposite sides of the motor 5. 80

There are two axles 8 at the rear or outer terminals of the arms 7. These axles, as here represented are in the form of screws passed through transverse openings in the arms 7 at their outer terminals, and held in place by means of nuts 9 and washers 10, together with the heads of the bolts, said axles being for two wheels 11 which are mounted thereon. The hubs, as 11', of the wheels 11 are mounted on the axles or bolts 8 outside of the arms 85 90, 95

7, the heads of said bolts are outside of said hubs, and the nuts 10 are inside of said arms, the washers 10 being interposed between said arms and said nuts.

3 The aforesaid non-rotary member is a foot comprising a holder 12 and an anti-slide member 13. The holder 12 has a cylindrical part 14 that is received in the open, bottom end of the socket member or socket 3, and also has an annular shoulder 15 upon which is received the under edge of said socket. The anti-slide member is recessed in the upper side, as represented at 16, to receive the bottom part of the holder 12, and said member is secured to said holder by means of a screw 17 which is passed upward through the axial center of said member to be tapped into the axial center of said holder.

20 The anti-slide member 13 is preferably made of rubber, and preferably has its bottom recessed to make of said member a suction cup. In the present example there are in the bottom of the member 13 a central recess 18 and an annular groove 19 for suction purposes. Thus it is seen that the anti-slide member not only grips or hugs the surface, with which it is in contact, in a manner to produce frictional resistance and thereby prevent sliding, but also forms a suction connection with such surface, whereby said member is held still more firmly in place thereon. While dependence for immovability might be placed on either the frictional-resistance factor, or on the suction factor, 25 either alone, it is preferred, for the sake of greater security, to provide and employ an anti-slide member which possesses both of these factors.

40 The transmission case 1 is preferably in the form of a hollow enclosure for containing transmission mechanism (not shown). The transmission will preferably be arranged to actuate shafts for a tub and a wringer as will be hereinafter referred to. 45 The case 1 functions as the body for the carriage and is in turn supported at opposite sides or ends by revolvable and anti-slide members and is sufficiently rigid to facilitate the rolling of the carriage about. This case 50 may be made of a plurality of secured together complementary sections as shown.

55 When the case 1 is in horizontal position, the bottoms of the wheels 11 and the bottom of the anti-slide member 13 are in the same horizontal plane. In other words, when the wheels 11 and the anti-slide member 13 all rest on the floor, the case 1 is in a horizontal position.

60 The case 1 has on top over the socket 3 a flange 20 into which is set and to which is pinned (at 21) a wringer column 22. At the upper end the column 22 has pinned thereto (at 23) a hub 24 of a handle 25. The handle 25 projects forwardly and is furnished to 65 facilitate raising the carriage at the front

end, moving the same, and again lowering it at said end.

The case 1 is provided adjacent to the rear end with upper and under flanges or hubs 26 and 27, respectively, for a shaft 28 driven from the motor 5 in the usual manner. A hub 29, of a tub support which comprises said hub and three arms 30, is mounted on and secured to the upper terminal of the shaft 28. A tub 31 is carried on the arms 30.

70 It will now be seen that the case 1, with the parts and members carried thereon and supported thereby, when normally disposed rests with the wheels 11 and the anti-slide member 13, of the foot at the front end, on the floor, and understood that the weight of the motor 5 is not sufficient alone to rock said case, through the medium of the arms 7, upwardly with the axles 8 as a center. The weight of the motor 5 is a factor, however,

80 in assisting to rock the case 1 upwardly on the wheels 11, said motor then swinging downwardly, when the handle 25 is grasped and said case is raised at the front end to take the anti-slide member 13 off of the floor, and also in assisting to balance the machine while still tilted and moved about by means of said handle. As soon as the upward force applied to the handle 25 is removed the case 1 rocks downwardly until the anti-slide member 13 again rests on the floor, carrying upwardly at this time the motor 5. The motor is always quite near to the floor and therefore prevents the machine from being upset rearwardly when tilted by means of the handle 25. The wheels 11 are so wide apart that tilting in a lateral direction is prevented.

90 The weight of the parts above on the anti-slide member 13 forces said member into close contact with the floor and thus causes 105 to be set up a degree of frictional resistance which in itself or alone frequently would be sufficient to hold said member in place, but in addition a partial vacuum is created in the recess 16 and the groove 19, and this adds sufficient additional staying force absolutely to prevent movement of the carriage in any direction until said member is lifted from the floor. The suction of the member 13 is not sufficient, however, to interfere with the raising of the carriage at the front end, and when said carriage is raised and said member is clear of the floor there is nothing to prevent moving the carriage on the wheels 11 in any direction.

120 In the carriage illustrated in the last two views, there are a single wheel, as 32, and two feet, as 33. The wheel 32 has an axle bolt 34 mounted in two bearings 35 depending from the bottom of the case 1 forward of the motor 5, said bolt being held in place by a nut 36. The feet 33 are fastened to two holders 37 that are received in socket members 38-38 located adjacent to the front end of said case. The socket members 37 extend

down alongside and below the sides of the front-end portion of the case. Otherwise the construction of the second carriage is practically identical with that of the first, and 5 the wheel 32 and the feet 33 respectively function in a very similar manner to that in which the wheels 11 and the foot 13 function, only in the one case the wheels at all times prevent the machine from tipping over sideways, and in the other case the feet when on the floor prevent the machine from tipping over sideways, but such tipping can only be prevented by the operator at such times as said feet are off of the floor, and the operator must balance the machine while being moved about on the single wheel. Ordinarily the first carriage is to be preferred.

The rotary and anti-slide members in the second carriage are smaller than corresponding members in the first carriage.

In Figs. 4 and 5 a flange 39 is shown beneath the body 1 and with the axis of said flange in line with the axis of the flange 20 above. The flange 39 is provided to assist 25 the associated flange 20 in supporting the column 22 set therein.

More or less change in the shape, size, construction, and arrangement of some or all of the parts of this carriage, in addition to those 30 hereinbefore specifically pointed out, may be made, without departing from the spirit of our invention, or exceeding the scope of what is claimed.

We claim:

35 1. A portable washing machine carriage comprising in combination, a body including a case for transmission mechanism, a tub shaft extending from the upper side thereof, revolvable and anti-skid members at opposite sides of said case below the same for supporting the same against movement along a floor or for allowing rolling movements thereof.

45 2. A portable washing machine carriage comprising in combination, a body including a hollow transmission case for enclosing transmission mechanism, a tub shaft extending upwardly from said case, revolvable and anti-slide members below said case at opposite ends thereof for supporting the same so that it may be rolled on said revolvable members or held against rolling movements by said anti-slide members in engagement with a floor.

55 3. A portable washing machine carriage comprising in combination, a hollow body formed from a plurality of secured together sections for enclosing transmission mechanism, a shaft extending from the upper side thereof and revolvable and anti-slide members at the lower side of the case for supporting the same whereby it may be rolled along a floor or held against rolling movements accordingly as the body is tipped 60 about the axis of the revolvable members.

4. A portable washing machine carriage comprising in combination, a body including bolted together hollowed out sections to provide a case for transmission mechanism, parts projecting downwardly therefrom which carry revolvable supporting wheels and anti-slip members whereby the body is supported for rolling movements along a floor or held against rolling movements.
